UNITED STATES PATENT OFFICE.

WILLIAM AUGUSTUS HUTCHINSON, OF CHARLESTON, SOUTH CAROLINA.

DRIER.

1,308,241.

Specification of Letters Patent.

Patented July 1, 1919.

Application filed September 3, 1918. Serial No. 252,362.

To all whom it may concern:

Be it known that I, WILLIAM A. HUTCHINSON, a citizen of the United States, residing at Charleston, Charleston county, and 5 State of South Carolina, have invented and discovered certain new and useful Improvements in Driers, of which the following is a specification.

My said invention consists of an improved 10 construction and arrangement of driers, its special purpose being to provide an apparatus for the drying of very light material, such as gypsum, graphite, or any similar substance, or any fluffy material which must 15 be dried without subjection to a draft, whereby a drier of such a type is provided that is very efficient in results and convenient of operation, as well as comparatively inexpensive to install, all of which as will 20 be hereinafter more fully described and claimed.

Referring to the accompanying drawings which are made a part hereof and of which similar reference characters indicate similar 25 parts,

Figure 1 is a top or plan view of an apparatus embodying my said invention,

Fig. 2, a side elevation,

Fig. 3, a cross section on the dotted line 30 3—3,

Fig. 4, a cross section on the dotted line 4—4, and

Fig. 5, a detail view showing one of the agitator plates in perspective.

35 In said drawings the portions marked A represent the supports, B the drier floor, or pans composing it, and C the hopper connected with the source of supply.

The frame comprises the supports A and 40 has guide rails 10 for the chain carriers and may be of any appropriate construction and arrangement for the purpose. In the front of the apparatus is a furnace having grate bars 11 connected by horizontal flues 12 45 with a chimney 13 at the other end of the apparatus.

The drying floor B consists of a series of sections or pans adapted to fit together and over the top of the furnace and flues constituting the heating apparatus, as shown, 50 making a continuous floor from one end of the apparatus to the other.

The feed hopper C is of any appropriate construction having a fluted, or angular in 55 cross section, feed roller 14 in its throat be-

ing adapted to be operated by power from any convenient source and arranged to receive the material from any convenient or appropriate supply. It is located directly above the front end of the drier and is 60 adapted to deposit material thereon.

An agitator is provided consisting of endless chains 15, one on each side, carrying transverse rods 16 at appropriate intervals on which tubular sections 17 are mounted each of which carries an agitator arm or plow 18 of substantially the form shown in Fig. 5. These arms hang upon the rods 16 so that they drag upon the floor B and are positioned with the angular ends 19 standing in one direction on one rod and in the other direction on the adjacent rods so that the agitator fingers of alternate rods project at reverse angles or those on one rod in a right-hand direction and those on the next 70 rods in a left-hand direction and insure that the material will be agitated, or turned, first in one direction and then in the other and at the same time dragged along over the drier bottom B from one end to the other. By referring to Figs. 1 and 2 this operation will be clearly understood. The upper part of each endless chain 15 runs upon one of the side parts or supports 10 with the agitator fingers thereon hanging in a vertical position. They pass over the drum 20 at one end and the drum 21 at the other end by which the endless chain or apron is driven. The driving chain 22 connects with a sprocket wheel 23 on the shaft 24 of frame 80 21 and furnishes the driving power. Another sprocket wheel 25 on the shaft 26 of the drum 20 is connected by a sprocket chain 27 with a sprocket wheel 28 on the shaft 29 of the feeding roller 14 in the hopper C. 90 95

At the end of the drier I form a transverse trough 30 in which is mounted a spiral conveyer 31 driven by a sprocket chain 32 from any appropriate power.

In operation, the material coming from the hopper C is gradually fed to the drier bottom B by the feed roller 14 and is dragged from one end of the drier bottom to the other by means of the agitator arms or plows 18 with their bent or angular ends 19, which operate to continually stir the material by moving it back and forth transversely and at the same time advance it, at each transverse movement toward the rear or discharge end of the drier bottom, bring- 100 105 110

ing it finally into the trough 30 from which it is discharged by the conveyer 31 to any convenient receptacle. The agitator arms drag upon the floor by reason of gravity the material being of such a light nature that comparatively light arms readily pass through the same, as will be readily understood. It will be understood of course that this drying apparatus is located in a closed room where it will not be subjected to wind or draft and its operation is continuous as above described.

The length of the apparatus may be such as required to accomplish the result and in some instances for some classes of work it will be readily seen that a longer drying surface is required than in other instances with other classes of work. The length of the apparatus will therefore be modified to suit conditions and other modifications in details will readily suggest themselves and can be made without departing from my invention.

Having thus fully described my said invention, what I claim as new and desire to secure by Letters Patent, is:

1. In a drier comprising a heater and provided with a drier floor constructed over said heater, an agitator comprising an endless apron with agitator arms pivoted on

transverse carriers at intervals and dragging therefrom, said agitator arms being formed with angular ends and arranged with part extending in one direction and part in another direction, whereby the material is agitated back and forth across the drier bottom and carried from end to end thereof, substantially as set forth. 35

2. In a drier comprising a heater and provided with a drier floor constructed over said heater, an agitator comprising an endless apron with agitator arms pivoted at intervals on transverse carriers to drag therefrom, said agitator arms being formed with angular ends and arranged a distance apart 40 in rows extending across the drier floor the angular ends of the fingers in alternate rows being disposed in opposite directions, whereby the material is agitated back and forth across the drier bottom and carried from end to end thereof, substantially as set forth. 45

In witness whereof, I have hereunto set my hand and seal at Charleston, South Carolina, this 27th day of August, A. D. 55 nineteen hundred and eighteen.

WILLIAM AUGUSTUS HUTCHINSON. [L. S.]

Witnesses:

ROBT. E. LEE,
D. A. BROCKINTON.
